Patented Dec. 17, 1968

212,998

ORANGE PEELER

Dean R. Kempf, 714 Heinel Drive,
St. Paul, Minn. 55113

Filed July 18, 1966, Ser. No. 3,249

Term of patent 14 years

(Cl. D89—1)

FIG. 1

FIG. 2

FIG. 3

FIG. 5

FIG. 4

FIGURE 1 is a perspective view of an orange peeler showing my new design;

FIGURE 2 is a bottom plan view of the same;

FIGURE 3 is a side elevational view of the same;

FIGURE 4 is a cross-sectional view, the position of the section being indicated by the line 4-4 of FIGURE 3; and

FIGURE 5 is a cross-sectional view, the position of the section being indicated by the line 5-5 of FIGURE 3.

I claim:

The ornamental design for an orange peeler, as shown.
